UNITED STATES PATENT OFFICE.

WILLIAM CHRISTENSEN, OF PHILADELPHIA, PENNSYLVANIA.

SAFETY DEVICE FOR STEAM-BOILERS.

SPECIFICATION forming part of Letters Patent No. 536,128, dated March 19, 1895.

Application filed February 14, 1894. Renewed December 16, 1894. Serial No. 531,971. (No model.)

To all whom it may concern:

Be it known that I, WILLIAM CHRISTENSEN, a citizen of the United States, residing at the city of Philadelphia, in the county of Philadelphia and State of Pennsylvania, have invented certain new and useful Improvements in Safety Devices for Steam-Boilers, of which the following is a specification.

My invention has relation to safety devices for steam boilers; and it relates more particularly to the arrangement of a fusible plug in connection with certain mechanism in proximity to the boiler as a means of safety and adapted to operate in the event of the fluid of the boiler sinking below the normal line thereof.

The principal object of my invention is to provide a simple, inexpensive and efficient safety device for a steam boiler and so arranged in connection with the piston and valve of the feed pipe of the boiler as to automatically operate the valve thereof in the event of the fluid of the boiler sinking or falling below the normal water line therein by the melting of a fusible plug by the steam of the boiler and of the same then pressing against the piston of a cylinder to actuate by the movement of the piston the said valve connected with the feed water pipe of the boiler.

My invention stated in general terms, consists of a boiler provided with a controlled pipe connection having a fusible plug interposed therein and adapted to establish a direct connection with a cylinder having a piston adapted to operate levers connected with a valve of the feed pipe of the boiler; and my invention further consists of the improvements hereinafter described and claimed.

The nature and scope of my invention will be more fully understood from the following description taken in connection with the accompanying drawings forming part hereof, and in which—

Figure 1, is a view partly in front elevation and partly in section of a steam boiler with a fusible plug safety device of my invention shown in application thereto; and Fig. 2, is a view partly in vertical central section through the fusible plug and a cylinder and piston and in elevation the levers and feed pipe of the boiler operated thereby, of Fig. 1, show-

ing the detailed construction and arrangement thereof.

Referring to the drawings A, is the boiler 55 of any suitable construction and arrangement showing the normal water line y, therein.

b, is a pipe connected with the head a', of the boiler, and provided with a stop-cock b'.

c, is a circular offset formed in the pipe b, 60 and having a threaded internal surface c', for the reception of a partially threaded fusible plug C. The pipe b, is extended and provided with a section b², secured into or formed integral with a cylinder D, and providing 65 thereby an inlet to the interior thereof.

d, is a piston adapted to be afforded an up and down movement and provided with a rod or stem d', pivoted at its opposite end to a rocking beam d², pivotally supported at d³, 70 from the head a', of the boiler A. At the opposite end of the rocking beam d², is pivoted thereto a lever d⁴, which is pivoted at its opposite end to the arm d⁵, of a cut-off valve e, suitably mounted in a water feed pipe E, 75 connected with the boiler A, and depending therefrom.

The operation of the safety device hereinbefore described, is as follows: It must be assumed that the fusible plug C, occupies the 80 position shown in Figs. 1 and 2, and that the mechanism adapted to be actuated to operate the valve e, of the pipe E, is in the position shown and with the stop-cock b', open. If the fluid in the boiler A, should for any 85 cause sink or fall beneath the low water line x, in the sectional view of Fig. 1, the steam will enter the pipe b, and in its passage will melt the fusible plug C, thereby forcing itself in a forward direction through the pipe b², 90 connected with the cylinder D, raising the piston therein, which in turn by means of its stem or rod d', will rock the beam d², and operate in a downward direction the lever d⁴, to automatically actuate the arm d⁵, of the valve 95 e, of the pipe E, to open the same and to permit water to flow into the boiler A, thereby preventing bursting thereof. When the boiler has been again filled with a fluid or restored to its normal state or condition by turning 100 the stop-cock b', so as to prevent the passage of steam from the boiler through the pipe b, another fusible plug C, may be inserted to place in the offset portion c, thereof adapted

to receive and support the same under normal conditions of the boiler, yet nevertheless adapted to readily fuse or melt under abnormal conditions such as hereinbefore explained.

Having thus described the nature and objects of my invention, what I claim as new, and desire to secure by Letters Patent, is—

1. A steam boiler having controlled pipe connections leading from the head thereof and provided with an offset supporting a fusible plug, said pipe connections in communication with a cylinder having a piston provided with a rod or stem connected with a rocking-beam actuating a lever pivoted to the arm of a valve in a feed pipe connected with the boiler, substantially as and for the purposes set forth.

2. A safety device for boilers, comprising a pipe connected with the head of the boiler at

or about the low water line thereof and provided with a stop-cock, an offset adjacent thereto with a threaded wall, a fusible plug engaging said offset and the latter having a connection with a vertical cylinder, a piston movable therein and provided with a stem pivoted to a supported rocking beam in pivotal connection with a lever attached to the operating arm of a cut-off valve of a pipe secured into the boiler and depending therefrom, substantially as and for the purposes set forth.

In testimony whereof I have hereunto set my signature in the presence of two subscribing witnesses.

WILLIAM CHRISTENSEN.
